Napoleon Bonaparte Bendy

UNITED STATES PATENT OFFICE.

NAPOLEON BONAPARTE BENDY, OF GALVESTON, TEXAS.

SASH-FASTENER.

SPECIFICATION forming part of Letters Patent No. 294,435, dated March 4, 1884.

Application filed June 25, 1883. (No model.)

To all whom it may concern:

Be it known that I, NAPOLEON BONAPARTE BENDY, a citizen of the United States, residing at Galveston, in the county of Galveston and State of Texas, have invented a new and useful Improvement in Window-Sash Fasteners, of which the following is a specification, with the accompanying drawings.

The object of my invention is to furnish a device by which window-sashes, when let down, are always fast or secure without having to be fastened or secured by hand, and when raised up catch on the stop or rest and securely hold the sash up without the trouble of fastening or securing by hand. These ends are attained by means of a piece of metal or other suitable substance, so formed and balanced and attached to the window-sash by a screw, and so placed on the sash that it will lie against the window-casing, which holds the sash in position, and immediately under another piece of metal or other suitable substance, so formed and attached to the window casing or frame that in attempting to raise the sash the piece on the sash will come in contact with the piece on the frame or casing and form a double catch, and thereby prevent the sash being raised; and when the sash is raised up the piece of metal on the sash will catch on the piece on the casing or frame and hold the sash securely in position, as will be seen in the drawings, in which—

Figure 1 is a perspective view of a window-sash in the frame, with my fastener attached when the sash is down; Fig. 2, a front view of the fastener when in contact with the stop; Fig. 3, a view of the same when the sash is raised; Fig. 4, a view of the same when raising or lowering the sash.

In the drawings, A is the fastener attached to the sash. B is the stop attached to the window frame or casing, one above and one below. The upper one is used as a rest to

hold the sash in position when raised, and the lower one when in contact with the fastener to form the double catch to prevent the sash from being raised. The stop B is firmly attached to the window casing or frame so as to hold it in the same position, while the fastener A is attached to the sash so that it will turn on the screw.

In order to raise the sash when down, the fastener A is turned bottom upward, and resting against the stop B, when the fastener will pass the stop in raising the sash; and in order to lower the sash after being raised and rested on the upper stop, the sash is slightly raised, so as to release the fastener from the stop and then turn the fastener bottom upward, so that it will rest against the window casing or frame, when the fastener will pass the stop and the sash will go down. The fasteners are to be made of any desired size and of any metals or composition or other substances capable of being used for the purpose of a fastener. They are intended to be used on windows, doors, elevators, and in all other places where applicable.

Having fully described my invention, what I desire to claim, and secure by Letters Patent, is—

The combination, with a window frame and sash, of a fastener consisting of stops secured to the frame and formed with beveled ends and a shoulder, as shown, and a button, A, pivotally secured to the sash and recessed to form a triangular projection, and a finger-piece extension, which latter serves also as a weight to effect an automatic fastening as the window is lowered, substantially as shown and described.

NAPOLEON BONAPARTE BENDY.
